CLAIM

The ornamental design for a medicament infusion pump device, as shown and described.

DESCRIPTION

This application is related to U.S. application Ser. No. 29/776,660, filed Mar. 31, 2021, titled Medicament Infusion Pump Device, which is incorporated by reference and made a part of this specification.

This invention was made with U.S. Government support under Contract No. DK120234, awarded by the National Institutes of Health. The Government has certain rights in the invention.

FIG. 1 is a front, first side, and top isometric view of a medicament infusion pump device embodying the new design;

FIG. 2 is a front, first side, and bottom isometric view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The dot-dash broken lines in the drawings define the bounds of the claimed design and form no part thereof. The dash-dash broken lines in the drawings depict portions of the medicament infusion pump device that form no part of the claimed design.

1 Claim, 6 Drawing Sheets
